US0D1112281S

(12) **United States Design Patent** (10) **Patent No.:** **US D1,112,281 S**
Edwards et al. (45) **Date of Patent:** **** Feb. 10, 2026**

(54) **DISPLAY SCREEN OR PORTION THEREOF WITH GRAPHICAL USER INTERFACE**

(71) Applicant: **Apple Inc.**, Cupertino, CA (US)

(72) Inventors: **Dylan Ross Edwards**, San Jose, CA (US); **Christopher Daryl Soli**, Mountain View, CA (US); **Brandon Marshall Walkin**, San Francisco, CA (US)

(73) Assignee: **Apple Inc.**, Cupertino, CA (US)

(**) Term: **15 Years**

(21) Appl. No.: **29/939,363**

(22) Filed: **Apr. 26, 2024**

Related U.S. Application Data

(63) Continuation of application No. 29/787,349, filed on Jun. 6, 2021, now Pat. No. Des. 1,040,815.

(57) **CLAIM**

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design. The broken lines within the peripheral dashed broken lines illustrate portions of the graphical user interface which form no part of the claimed design.
